(57) CLAIM

The ornamental design for a beverage holder, as shown and described.

DESCRIPTION

FIG. 1 is a perspective view from above and one side of a beverage holder according to my design;

FIG. 2 is a front end elevational view of the beverage holder;

FIG. 3 is a rear end elevational view of the beverage holder;

FIG. 4 is a top plan view of the beverage holder;

FIG. 5 is a bottom plan view of the beverage holder; and,

FIG. 6 is a side elevational view taken from the right side of FIG. 2, the opposite side being a mirror image.

1 Claim, 3 Drawing Sheets
